UNITED STATES PATENT OFFICE.

ANTON AUMÜLLER, OF MUNICH, GERMANY.

HOOD OF MOTOR-CARS.

1,074,232.

Specification of Letters Patent. Patented Sept. 30, 1913.

Application filed May 6, 1912. Serial No. 695,539.

To all whom it may concern:

Be it known that I, ANTON AUMÜLLER, citizen of Germany, residing at Munich, Bavaria, Germany, have invented certain new and useful Improvements in Hoods of Motor-Cars; and I do hereby declare the following to be a full, clear, and exact description of the invention, such as will enable others skilled in the art to which it applies to make and use the same.

This invention relates to improvements in the hood of motor cars or other vehicles consisting in the particular arrangement and construction of the front- and side-windows which may be easily raised and lowered and whereby the management of the hood of the carriage is rendered simple and easy. Especially this new mechanical arrangement renders unnecessary any buttoning which in sail-cloth-hoods is very troublesome. Besides the uprights which in wholly hooded cars are necessary, may be omitted.

It is the object of the invention to provide a sliding carriage window which in its elevated position is secured against lateral displacement and which when used with automobiles permits of a tight engagement between the front and the side windows in such a way that the customary comparatively strong corner posts can be dispensed with. These are the posts at the front of the automobile between which the front windows are guided and into which the vertical front branches of the frame for the two lateral sliding windows are guided in the elevated position. In order to obtain this result applicant guides each of his sliding windows in a metal frame having three branches and being opened at the top, said frame following the movement of the window to a certain extent if the window is raised, whereafter suitable stops prevent further movement of said frame and permit the window to be further raised without the frame into its final elevated position. The frame itself then rests in an intermediate position within the trap of the window and secures the window against lateral movement. The branches of this three-branch frame have a U-shaped cross section.

In the accompanying drawing is represented an apparatus embodying the invention.

Figure 1 is a view with partial section illustrating a motor car with the new hood;

Fig. 2 is a horizontal section according to the line A—B of Fig. 1. Fig. 3 is a vertical section through the side-window according to the line C—D of Fig. 2.

In Figs. 4 and 5 is represented an arrangement which serves for fixing the side-window. Fig. 4 shows a section according to the line E—F of Fig. 5 which is a horizontal section of Fig. 4.

The front-window *a* which may be lowered, extends across the entire width of the car and has on the sides of its frame *b* a groove *c*. In these grooves are arranged the corresponding legs of the frames *e* of the side-windows *d*, when the latter are raised. In the drawing this metal frame is shown at *g* for the side window, and *f*, *k* for the front window.

g, *f* are the vertical side branches having a U-shaped cross section and *l* and *k* designate the lower horizontal connecting members. The latter however need not have a U-shaped cross section.

The stopping device for arresting the travel of the frame during the elevation of the windows consists of two suitably bent tongues *i* upon the inner face of the lower frame *l*, said tongues being upwardly directed and are engaged when the window is raised by the cross-rod *m* of the door frame, above the same.

During the closing action of the sliding window its strengthening frame will participate in its movement until its tongues *i* engage the cross-rod *m*. Then the movement of the frame will be stopped and the window continues to slide along in its guides until it is closed.

The intermediate position of the strengthening frame is chosen in such a manner that it is secured against lateral movement within the trap and extending to a sufficient distance out of the same to securely hold the window in a raised position against lateral movement.

In order to insure the proper working of the frame during its participation in the movement of the window until it reaches the above mentioned intermediate position, the window is guided within U-shaped vertical branches *e* and *f* with a slight friction. This can be effected in different ways, for instance by slightly inclining the vertical branches of the frame toward each other at the top so that the upper width of the strengthening frame is slightly less than the

lower, or in order to obtain such a frictional effect the U-shaped cross section may be somewhat modified to suit the purpose. Each frame can also suitably be provided at 5 its upper branch ends with a step tongue h directed toward the inside. The same is true with respect to the front window a .

In order to do away with the front corner or edge post according to the drawing, the 10 front frame b of the sliding window is provided upon both of its sides with lateral grooves c into which the vertical front branches g of the strengthening frame of the side window are engaging if the window is 15 raised. In this manner a tight connection between the front and the side sliding windows is obtained and a rattling during the motion of the vehicle is avoided. It is clear that the lateral grooves c in the vertical 20 front branches of the frame for the side windows may just as well be arranged in such a manner that the strengthening frame of the front window engages the grooves.

The locking of the side-windows in closed 25 or partly opened position is effected by means of the arrangement according to Figs. 4 and 5. For this purpose two yielding press plates n are provided which are fixed 30 on a locking trap o and squeeze the window frames e in the slide groove p by means of the parts g .

The locking of the trap o which may be turned around the hinge joints g and lowered is effected by means of rocking bolts s and 35 the rocking-plate r . The press plates n can be pivotally arranged on the rocking-bolts s which latter penetrate in the lock-holes z like wedges. Before raising or lowering the 40 window, the trap o is opened, to lock the window the trap o must be shut and locked.

The latch rods s enter the openings z in the manner of a wedge in order to obtain the most effective clamping of the rods m against the window so that the window is 45 securely held in partially or totally opened position. Before the window changes its

position the adjoining trap must be opened in order to make the window free from the action of the presser plate.

The hood of the motor car consists of 50 bows, the joints w of the front-bow lie deeper than the joints u' of the back bows. When the hood is folded together, the front bow therefore comes to lie sufficiently backward, whereby double-joints, which had 55 been necessary hitherto, may be omitted.

What I claim is:

1. A window holder for motor cars or other vehicles, comprising a three-branched metal frame of U-shaped cross section for 60 each front and side window, open at the top and adapted to partially participate in the movement of the windows, and provided with lateral grooves, each adapted to secure the metal frame of the adjoining front or 65 side window, means upon the inner faces of the lower frames for arresting the upward movement at a predetermined point, and means at the upper end of each frame for increasing the frictional engagement between the frame and the walls of said 70 groove, substantially as described.

2. A window holder for motor cars or other vehicles, comprising a three-branched metal frame of U-shaped cross section for 75 each front and side window, open at the top and adapted to partially participate in the movement of the windows, and provided with lateral grooves, each adapted to secure the metal frame of the adjoining front or 80 side window, stop tongues upon the inner faces of the lower frames for arresting the upward movement at a predetermined point, and an inwardly directed stop tongue at the 85 upper end of each frame, substantially as described.

In testimony whereof I hereunto affix my signature in the presence of two witnesses.

ANTON AUMÜLLER.
